MACHINE FOR PRINTING MAILING PIECES FROM DUPLICATING CARDS

Harry R. Frankle and Perry T. Crane, Des Moines, Iowa

Application November 12, 1954, Serial No. 468,422

5 Claims. (Cl. 101—52)

This invention relates generally to printing machines and in particular to a machine and method for printing names and addresses on mailing cards, magazine certificates, envelopes and the like. As used herein the term "mailing piece" shall include envelopes, cards, magazine certificates, letters and the like wherein the material to be printed is in a generally sheet form.

In printing machines of this general type the duplicating cards carry on one side thereof an imprinted transferable carbon type. These duplicating cards are continuously introduced, in a predetermined relation, with corresponding mailing pieces, between a presser or printing cylinder and a rotatable platen unit, to provide for the transfer or printing of the carbon type from the duplicating card onto the mailing piece. By virtue of the transfer characteristic of the carbon type on the duplicating cards, the printing of the mailing pieces is usually accompanied by some smearing of this type as a result of its contact with portions of the feed or the conveying mechanism for the duplicating cards. Also, smearing of the printing on the mailing pieces results from the fact that the printing cylinder and the platen unit are operated at different peripheral speeds, so that the duplicating cards and mailing pieces are moved relative to each other as they pass together in a printing operation between the cylinder and the platen unit. A further objection in machines of this type is found in the fact that on completion of a printing operation difficulty is encountered in efficiently separating the duplicating cards from the mailing pieces.

It is an object of this invention, therefore, to provide an improved machine and method for printing mailing pieces from duplicating cards.

A further object of this invention is to provide a printing machine wherein a duplicating card with a carbon transfer type on one side is taken from a stack, fed into a printing zone in a carbon transfer relation with a mailing piece, and then removed from the printing zone, with such one side of the card out of contact engagement with any of the conveying means for the duplicating cards, whereby to eliminate any smearing of the carbon transfer type.

Another object of this invention is to provide a machine in which a rotary platen unit is provided with a floating segmental member, yieldably biased to a neutral position therefor, and adapted for contact engagement with a co-acting presser or printing cylinder. The platen segment and cylinder are of the same diameter and operated at the same speed, and on introduction of a duplicating card and mailing piece therebetween the segmental platen member is oscillated or rocked relative to the platen unit to maintain the cylinder and platen segment at the same peripheral speed during a printing operation, whereby to eliminate any relative movement between a duplicating card and a mailing piece during the printing operation.

Still another object of this invention is to provide a machine in which a duplicating card is fed to a printing

2

cylinder by a conveyor means, and then picked up by and retained against the cylinder for travel therewith in the zone of printing engagement with a mailing piece. On completion of the printing operation the duplicating card is released from the cylinder to free the cylinder to take on a next succeeding duplicating card.

Yet a further object of this invention is to provide a machine wherein a duplicating card and a corresponding mailing piece are introduced between a printing cylinder and an associated platen unit in a transversely offset relation so that a side portion of the mailing piece extends laterally outwardly from the adjacent side portion of the duplicating card. As the card and mailing piece pass outwardly from between the cylinder and platen unit, the laterally extended side portion of the mailing piece is engaged by a guiding and deflecting member whereby to separate the mailing piece from the duplicating card and to guide the mailing piece onto a discharge conveyor therefor.

Still a further object of this invention is to provide a machine for printing a mailing piece from a carbon transfer type duplicating card which is of a simple construction, fast in operation, and capable of performing an efficient printing operation without smudging or smearing of the carbon on the mailing piece.

Further objects, features and advantages of this invention will become apparent from the following description when taken in connection with the accompanying drawing in which:

Fig. 1 is a perspective view of a machine for printing on a mailing piece from a duplicating card, embodying the improved printing mechanism and method of this invention;

Fig. 2 is an enlarged fragmentary perspective view showing the printing cylinder and platen unit assembly of this invention, with certain parts being broken away to more clearly illustrate its construction;

Fig. 3 is a side elevational view of the printing cylinder and platen unit assembly in Fig. 2 showing a deflecting member for separating a mailing piece from a duplicating card after a printing operation;

Fig. 4 is a sectional view taken substantially along the line 4—4 in Fig. 3, showing the arrangement of a mailing piece and a duplicating card relative to each other and to the separating or deflecting member during a printing operation;

Fig. 5 is a perspective diagrammatic view of the power transmission system for the machine of this invention with the operating elements shown in a spaced apart relation to more clearly illustrate the driving means therefor; and

Figs. 6, 7 and 8 are diagrammatic showings of the printing cylinder and platen unit showing changed positions thereof in a complete cycle of operation.

With reference to the drawings there is illustrated in Fig. 1 a printing machine of this invention including a main frame 15 of a generally rectangular shape having at one end 16 a mechanism 17 for picking up mailing pieces 18 from a holder 19. The mailing pieces 18 are fed, from the pick-up mechanism 17, in an end to end relation into a conveyor 21 for movement between the lower side 20 of a presser or printing cylinder 22 and a cooperating platen unit 23 (Fig. 2), which are located substantially intermediate the ends of the machine frame 15.

Mounted on the opposite end 24 of the machine frame 15 (Fig. 1) is a mechanism 26 for picking up duplicating cards 27 from a duplicating card holder 28 for transfer onto a conveyor 29, in an end to end relation, which conveys the duplicating cards 27 to the upper side 25 of the printing cylinder 22. A duplicating card 27 is

then picked up by the cylinder 22, for rotation therewith between the cylinder 22 and the platen unit 23 at the lower side 20 of the cylinder 22 for printing onto a mailing piece 18. The portions of the cylinder 22 and platen unit 23 in contact or printing engagement thus constitutes the effective zone of a printing operation.

On completion of a printing operation, the mailing pieces are separated from the duplicating cards 27, with the mailing pieces 18 being transferred to a conveyor 31 for removal to a suitable receiving receptacle (not shown) provided on the frame 15. In turn the separated duplicating cards 27 are transferred from the cylinder 22 to a conveyor 32 for movement to a receiving receptacle (not shown) on the frame 15.

As shown in Figs. 2 and 4, the printing cylinder 22 is of a hollow construction and has at one end a hub 30 which is rotatably supported on a stationary tubular shaft 33. The other end 34 of the cylinder 22 is provided with a shaft 36 rotatably carried in a suitable bearing (not shown).

The hub 30 is formed with a circular air inlet 37 (Fig. 2) adapted for registration with an air inlet 38 formed in the tubular shaft 33 such that registration of the inlets 37 and 38 is effected once during each revolution of the printing cylinder 22. The tubular shaft 33 is suitably connected with an exhaust or vacuum pump 39, indicated in Fig. 5, which is operated by a motor 41.

Formed in the periphery of the printing cylinder 22 (Fig. 5) is an air inlet 42 of a substantially rectangular shape and located on the cylinder 22 so as to be in the path of movement of the duplicating cards 27 as these cards leave the conveyor 29.

It is seen, therefore, that during the period of rotation of the cylinder 22, providing for the air inlets 37 and 38 being out of registration, air is drawn into the cylinder 22 at the inlet 42 thereof whereby to provide a suction effect at the cylinder inlet 42. This suction action at the cylinder inlet 42 is relieved during those times when the inlets 37 and 38, for the cylinder hub 30 and shaft 33, respectively, are in registration with each other.

The platen unit 23 (Figs. 2 and 4) is comprised of a disc member 43 mounted on a shaft 44 for rotation with such shaft. A segmental platen member 46 is carried at the free end of an arm 47 which is rotatably mounted on the shaft 44 at a position adjacent to the disc 43. The arc of curvature of the segment 46 is greater than the arc or circle of the disc 43, and is generated with a radius equal to the radius of the printing cylinder 22. It is seen, therefore, that the platen segment 46 is capable of being oscillated or rocked about the shaft 44 and relative to the disc 43, so as to be in what might be termed a floating relation relative to the disc 43.

As best appears in Fig. 2 the platen segment 46 is biased toward a neutral or centered position, relative to the disc 43, by the provision of a pair of coil springs 48 having one of their ends secured to a common pin 49 attached to and extended laterally from the segment 46, and the opposite ends thereof secured to laterally extended pins 51 carried in an angularly spaced relation on one side of the disc 43. Any oscillating or rocking movement of the platen segment 46, relative to the disc 43, is thus resisted by one or the other of the coil springs 48 which, acting together, tend to maintain the platen segment or member in a neutral position against the action of any force tending to move the segment member 46 from such neutral position.

As previously mentioned the outer peripheral surface of the platen member 46 is generated with a radius equal to the radius of the outer periphery of the cylinder 22. Likewise the cylinder 22 and the platen unit 23 are rotated at the same rate so as to maintain the peripheral speeds of the cylinder 22 and the platen member 46 the same, it being understood that the rotation of the platen member 46 is effected through the coil springs 48.

Thus, on the introduction of a mailing piece 18 and a

duplicating card 27 between the cylinder lower side 20 and the platen member 46 the tendency of adjacent faces of a card 27 and mailing piece 18 to be moved at different rates of speed by virtue of the different thicknesses thereof is compensated for by the oscillating action of the platen member 46. In other words, the speed of travel of the outer face of the card 27 depends on the thickness thereof, which in effect increases the radius of the cylinder 22.

Likewise, the speed of the side to be printed on of a mailing piece 18 is dependent on the thickness of the piece 18. Since the cylinder 22 and platen member 46 have equal radii and are driven at the same rates of speed it will be appreciated that the action of the platen member 46 need be great enough to compensate for only

slight variations in the relative speeds of the adjacent faces of a card 27 and a mailing piece 18 on the cylinder 22 and platen member 46, respectively with the oscillating or slipping action of the platen member in opposite directions being dependent on the frictional pressure effected

by a mailing piece 18 and card 27 as they pass between the lower side 20 of the cylinder 22 and the platen member 46. By virtue of this compensating action of the platen member 46 relative slipping movement between a mailing piece 18 and a duplicating card 27 is eliminated during a printing operation to in turn eliminate any smearing in the carbon transfer from a duplicating card to a mailing piece.

A mailing piece 18, when discharged from the conveyor 21, is picked up between a pair of driven rolls 52 and 53 (Figs. 2 and 7) for travel therethrough at a rate equal to the peripheral speed of the cylinder 22. From the rollers 52 and 53 a mailing piece 18 is directed between the lower side 20 of the cylinder 22 and the platen unit 23, so as to be at such lower side 20 when the platen segment or member 46 is opposite the cylinder 22.

This timed or synchronized passage of the mailing piece 18 is accomplished by the provision of a pivoted trip gate 54, located at the discharge end of the conveyor 21. When the trip gate 54 is closed, a mailing piece is retained thereagainst, and in sliding engagement relative to the conveyor 21. On pivoted movement of the gate in a direction away from the discharge end of the conveyor 21, the mailing card is released for travel between the rollers 52 and 53, with this release action being

timed in response to the rotation of the cylinder 22, as will be later described.

A duplicating card 27 (Fig. 6) on being discharged from its associated conveyor 29, has the forward or leading end thereof drawn against the peripheral surface of the printing cylinder 22 by the suction action at the cylinder air inlet 42. As a result of this retention a duplicating card 27 is rotatable with the cylinder 22 at the same rate of speed as the cylinder 22.

During its rotational movement with the cylinder 22, a duplicating card 27 is maintained against the cylinder by the provision of a retaining member 56 (Figs. 3 and 6) having one end 57 extended within the discharge end of the conveyor 29 at a position above a duplicating card 27 carried on such conveyor. In other words, the duplicating card 27 passes beneath the retaining member 56.

From its end 57 the retaining member is extended in a concentrically spaced relation about the cylinder 22 from its upper side 25, and about its lower side 20 for termination of its opposite end 58, within, and above the receiving end of the conveyor 32. As a result, a duplicating card 27, from the discharge end of the conveyor 29, to the receiving end of the conveyor 32 is moved between the periphery of the cylinder 22 and the retaining member 56.

The discharge of a duplicating card 27 from the conveyor 29 is controlled by the action of a pivoted trip gate 59 (Fig. 6) extended across the discharge end of the conveyor 29, and similarly to the action of the trip gate 54 for a mailing piece 18. When the trip gate 59 is closed a duplicating card 27 is held thereagainst in

sliding engagement with the conveyor 29. On pivoted movement of the trip gate 59, away from the discharge end of the conveyor 29 to an open position, a duplicating card 27 is released at substantially the same time that the cylinder air inlet 42 is at the upper side 25 of the cylinder 22, so as to be picked up by the cylinder for rotation therewith. The opening and closing movement of the trip gate 59 is operated in response to, and in a timed relation, with the rotational speed of the cylinder 22, as will later appear.

As shown in Fig. 2 the retaining member 56 for a duplicating card 27 is in contact engagement with a card 27 over a side portion 61 thereof free of any carbon transfer type, so that the type side portion 62 is free of any contact with the retaining member 56. In this same connection it is to be noted that a duplicating card 27 has the unprinted side thereof resting on the conveyor 29, so that when a card 27 is in a held position by the trip gate 59, the movement of the conveyor 29 relative to the card 27, is without any action on the carbon type carried on the card side portion 62.

Referring to Fig. 4, a duplicating card 27 and a corresponding mailing piece 18 are introduced into the printing zone between the lower side 20 of the cylinder 22 and the platen member 46 in a transversely offset relation such that the side portion 61 of the duplicating card 27 projects inwardly toward the cylinder end 34 away from the corresponding side portion 63 of a mailing piece 18, and the side portion 64 of the mailing piece 18 extends laterally outwardly from the carbon impressed side portion 62 of a duplicating card 27. Stated another way, in passing through the printing zone only the side portions 63 and 62 of a mailing piece 18 and duplicating card 27, respectively, are in a superposed relation.

Positioned between the lower side 20 of the cylinder 22 and the side portion 64 of a mailing piece 18 is a deflecting or separating member 66 (Figs. 3 and 4) having one end 67 positioned adjacent the discharge side of the rollers 52 and 53 at a position above a card 18 passing from between such rollers. The opposite end 68 of the separating member 66 extends within and above the receiving end of the conveyor 31.

Thus, on travel of a mailing piece 18 and corresponding duplicating card 27, from between the lower side 20 of the cylinder 22 and the platen unit 23, the duplicating card is guided by the end portion 58 of the retaining member 56 into the receiving end of the conveyor 32. However, the mailing piece 18, by virtue of the location of the side portion 64 thereof below the separating member 66, is separated from the duplicating card 27 and directed or guided for reception into the receiving end of the conveyor 31.

It is apparent, therefore, that the offset side portion 61 of a duplicating card 27 co-acts with the retaining member 56 to support a duplicating card about the cylinder 22, while leaving the carbon carrying side portion 62 of a card 27 exposed, and that the offset side portion 64 of a mailing piece 18 coacts with the separating member 66 in effecting a separation of a card 27 from a mailing piece 18 after a printing operation.

With reference to Figs. 6, 7, and 8 there is diagrammatically illustrated a complete cycle in the printing of a mailing piece 18 from a duplicating card 27. Thus, as shown in Fig. 6, the air inlets 37 and 38 for the cylinder hub 30 and shaft support 33, respectively, are out of registration when the air inlet opening 42 for the cylinder 22 is at the top side 25 of the cylinder. At such time, a duplicating card 27 is released by the trip gate 59 from the conveyor 29 for attachment of the leading end of the card 27 with the cylinder 22 at the air inlet 42. Concurrently, a mailing piece 18 is released by the trip gate 54 from the conveyor 21 for travel between the rollers 52 and 53 toward the lower side 20 of the cylinder 22. The relative release of a duplicating card 27 and mailing piece 18 from their corresponding conveyors 29 and 21,

respectively, is such that as a card 27 and a mailing piece 18 travel between the cylinder 22 and the platen member 46, as shown in Fig. 8, the carbon type on a duplicating card 27 is opposite the portion on a mailing piece 18 to be printed.

As a duplicating card 27 and corresponding mailing piece 18 leave the printing zone between the cylinder 22 and platen member 46 the air inlet openings 37 and 38 in the hub 30 and shaft 33, respectively, are moved 10 into registration as shown in Fig. 8. As a result, the suction effect at the cylinder air inlet 42 is relieved and the air chamber within the cylinder 22 is by-passed by the travel of air directly through the inlets 37 and 38. The duplicating card 27 is then removed from about 15 the cylinder 22 by the action of the end portion 58 of the retaining member 56, and separated from its corresponding mailing piece 18 by the action of the end portion 68 of the separating member 66 on the mailing piece. On rotation of the air inlet 42 to the top side 25 of the cylinder 22 the cycle of operation is repeated.

With reference to Fig. 5 there is diagrammatically illustrated the power transmission system for the machine of this invention. The printing cylinder 22 at its end 34 has the shaft 36 provided with a gear 72 and a pulley 73 which is belt connected with a pulley 74 mounted on the shaft of a driving motor 76. The shaft 36 thus constitutes a main drive or power shaft.

Also mounted on the shaft 36 is a cam member 77, of an adjustable type relative to the shaft 36, which is selectively engageable with the free end 78 of a rocker arm 79 attached to the pivot 81 for the duplicating card trip gate 59. The shaft 36 rotates in a clockwise direction, as viewed in Fig. 5, so that on engagement of the cam 77 with the rock arm 79 the trip gate 59 is pivoted outwardly 35 from the discharge end of the conveyor 29.

The gear 72 is in continuous meshing engagement with a like gear 82 mounted on the shaft 44 for the platen unit 23. The gear 72 is also in continuous meshing engagement with a gear 83 which in turn engages a gear 71 40 mounted on the shaft 84 of the drive roller 86 for the conveyor 31. The shaft 85 of the drive roller 87 for the conveyor 32 carries a gear 88, which is driven from the gear 71 through an idler gear 89. The shaft 90 of the drive roller 91 for the conveyor 29 carries a gear 95 45 which is driven from the gear 72 through an idler gear 92.

A sprocket gear 96, on the cylinder shaft 36, is chain connected with a sprocket gear 97 mounted on a counter shaft 98. This shaft 98, has adjustably mounted thereon 50 a cam 101 engageable with one end 102 of an arm 103 pivotally mounted at 104. The opposite end of the arm 103 is pivotally connected at 106 with one end of a link member 107 the opposite end of which is pivotally connected at 108 with a rock arm 109 carried on the pivot 111 for the trip gate 54. With the shaft 98 rotating in a clockwise direction, as viewed in Fig. 5, it is seen that on engagement of the cam 101 with the end 102 of the arm 103 the gate 54 is pivoted outwardly from the discharge end of the conveyor 21.

60 The feed rollers 52 and 53 for the mailing piece 18 have gears 112 and 113 thereon in continuous meshing engagement, with the gear 112 being in continuous meshing engagement with an idler gear 114 driven from a gear 115 on the counter shaft 98. A gear 116 carried on the shaft 117 of the drive roller 118 for the conveyor 32 65 is driven from the idler gear 114 through another idler gear 119.

It is seen, therefore, that all of the operating elements 70 of the machine are driven from and in a timed relation with the main power shaft 36 for the printing cylinder 22, and with the cams 77 and 101 for actuating the trip gates 59 and 54, respectively, being relatively adjustable to provide for the desired release of the mailing piece 18 and duplicating card 27 from their respective conveyors 21 and 29. The vacuum pump 39, for exhausting

air from within the cylinder 22, is provided with its own drive motor 41, as previously described.

Although the invention has been described with respect to a preferred embodiment thereof, it is to be understood that it is not to be so limited, since changes can be made therein which are within the full intended scope of the invention as defined by the appended claims.

We claim:

1. In a machine for printing mailing pieces from duplicating cards comprising, a rotatable presser cylinder, a rotatable platen member having a portion thereof adapted to contact said cylinder in printing engagement therewith, means movably supporting said platen portion on said platen member for yieldable oscillating movement relative to said platen member, means for feeding duplicating cards in succession between said cylinder and platen portion, means for feeding mailing pieces in succession between said cylinder and platen portion, means for relatively controlling said two feeding means so that a section of a mailing card to be printed is opposite a printing section on a duplicating card on passage of a duplicating card and mailing piece between said cylinder and platen portion, with the oscillating movement of said platen portion relative to said platen member acting to compensate for speed variations of adjacent surfaces of said cards.

2. In a machine for printing mailing pieces from duplicating cards comprising, a rotatable presser cylinder, a platen member arranged adjacent said presser cylinder, means mounting said platen member for rotation in printing engagement with said cylinder and for slipping movement relative thereto, means for feeding a duplicating card and a mailing piece in contact engagement with each other between said cylinder and platen member for printing on said mailing piece from said duplicating card, and with said mounting of the platen member providing for a slipping thereof during printing on a mailing piece to compensate for any difference in the relative speeds between said mailing piece and the duplicating card in engagement therewith to prevent any relative slipping of said cards.

3. In a machine for printing a mailing card from a duplicating card comprising a rotatable presser cylinder, a shaft substantially parallel to said cylinder, a disc member mounted on said shaft for rotation therewith, a segmental platen member of a diameter corresponding substantially to the diameter of said cylinder arranged in a concentric relation with and supported on the periphery of said disc, an arm member secured to said platen member and mounted about said shaft to provide for rotational movement of said arm and platen member relative to said disc, spring means connected to said platen member and extended in opposite directions therefrom for attachment to said disc to provide a yieldable resistance to the rotation of said arm and platen member, means for mounting one of said cards about said cylinder for rotation therewith, means for feeding the other one of said cards between said one card and said platen

member, with the mounting of said platen member providing for a limited rotation thereof relative to said disc to compensate for any differences in speed between adjacent faces of said cards to prevent any relative movement therebetween.

4. In a machine for printing a mailing card from a duplicating card comprising a rotatable presser cylinder, a shaft substantially parallel to said cylinder, a disc member mounted on said shaft for rotation therewith, a 10 platen member movably supported on the periphery of said disc, means yieldably holding said platen member for rotation with said disc and providing for a limited rotational movement relative thereto, means for releasably mounting one of said cards about said cylinder 15 for travel therewith, means for feeding the other one of such cards between said one card and said platen member, with the yieldable mounting of said platen member providing for a limited rotation thereof relative to said disc during travel of said cards therebetween to compensate for any differences in speed between adjacent faces of said cards so as to prevent any relative movement between the cards.

5. In a machine for printing mailing pieces from duplicating cards comprising a rotatable presser cylinder, a 20 rotatable platen member adapted to contact one side of said cylinder, means for feeding duplicating cards between said cylinder and platen member, means for feeding mailing pieces between said cylinder and platen member such that a side portion of a mailing piece is 25 laterally offset from a corresponding side portion of a duplicating card, and means engageable with said one of said offset side portions, after the passage of a mailing piece and a duplicating card from between said cylinder and platen member, to separate a duplicating card 30 from a mailing piece, said means engageable including a retaining member in a concentrically spaced relation with said cylinder at a position between said one side and an opposite side thereof, and a pair of conveyor means, corresponding to separated duplicating cards and mailing pieces, for receiving said duplicating cards and mailing pieces from said separating means.
